CHRISTMAS TREE BASE

Olin Trogdon, Hudson, Ohio

Application January 20, 1951, Serial No. 206,982

7 Claims. (Cl. 248—48)

1

This invention relates to a mounting base for supporting and holding in upright position a pole or pole-like structure such as the trunk of a Christmas tree. The invention embodies a flexible base formed of crossed spring like members on which are carried a pair of brackets adjustable in respect to those members to grip the lower end of the pole or tree trunk as the case may be, taking advantage of the tendency of the base members to bend downwardly centrally under the load of the tree, whereby the brackets carried by those members tend to tilt inwardly by their upper ends to increase a gripping action on the pole or trunk.

Furthermore the invention embodies a self-leveling feature due to the elasticity and bending action of the cross members, also at the same time contributing to an anti-skid control of the stand on a floor.

With these features constituting advantages and purposes of the invention, kept in mind, one particular form of the invention is herein described in reference to the accompanying drawing, in which

Fig. 1 is a view in top plan of a structure embodying the invention with a lower section of a tree trunk clamped thereon;

Fig. 2 is a view in inside elevation of one of the clamps on an enlarged scale;

Fig. 3 is a view in top plan of the bracket;

Fig. 4 is a view in vertical section on the line 4—4 in Fig. 2;

Fig. 5 is a view in vertical section on the line 5—5 in Fig. 1 on an enlarged scale;

Fig. 6 is a view in inside elevation of a second clamp;

Fig. 7 is a horizontal transverse section on the line 7—7 in Fig. 6; and

Fig. 8 is a view in top plan in fragmentary showing of the intersecting of the cross members with the brackets installed thereon.

I provide a base made out of two identically shaped bars 10 and 11, herein shown as in the nature of lengths of strap iron. Each of these bars 10 and 11 is provided with a foot, Fig. 5, generally designated by the numeral 12 wherein there is a length 13 of the bar turned downwardly and outwardly to a lower bend 14 from which the bar continues upwardly by a short terminal end 15. This foot 12 in each instance serves as means to space the bars 10 and 11 throughout their major lengths upwardly from the floor or other substance upon which the stand is to be positioned.

In each case, the bars 10 and 11 is centrally

drilled to receive therethrough a bolt 16. These bars 10 and 11 are normally positioned to be at right angles to each other as indicated in Fig. 1.

A pair of brackets generally indicated by the numerals 17 and 18 are provided to be carried by these 10 and 11.

The bracket 17 is provided with two flat plate portions 19 and 20 lying approximately in a common plane, and separated by an intervening integral V-shaped portion 21 which is composed of the wings 22 and 23, Fig. 6, pressed outwardly from between those portions 19 and 20. That is these portions 22 and 23 define a V in cross section as indicated in Fig. 7. The portions 19 and 20 are carried below the lower end of the V portion 21, Fig. 6, to have opposing fingers 24 and 25 extending one toward the other as continuations of the lower ends of the portions 19 and 20 to be in the same plane therewith. The top edges 26 and 27 respectively of these fingers 24 and 25 are spaced below the bottom edge 28 of the V portion 21 as indicated in Fig. 6.

This lower edge 28 however is not in a straight line, but dips down to the central point 29. That is this point 29 is lower than are junctions of the portions 22 and 23 with the portions 19 and 20 as at 30 and 31.

This bracket 17 is engaged with one of the bars 10 and 11 herein shown as with the bar 11. In this case the bar 10 crosses over the top of the bar 11. The bar 11 is passed through the space under the edge 28 and over the fingers 24 and 25 to bring it in some such position as indicated in Fig. 5. The bracket is then in contact with the top side of the bar 11 at the point 29, and in contact with the underside of the bar 11 by the edges 26 and 27 of the fingers 24 and 25.

The bracket 18 is formed to have two portions 32 and 33 flat in nature and in the same plane, with an intervening fold into a V-shape as defined by the portions 34 and 35 bending from the portions 32 and 33 to the apex bend 36. The portions 32 and 33 each carry respectively the in-turned feet 37 and 38, flat and in the same plane, to extend one toward the other and terminate by the spaced edges 39 and 40, these edges being positioned as indicated in Figs. 2 and 3. The spacing apart of the edges 39 and 40 is less than the transverse width of either of the bars 10 or 11. The lower edge 41 extending across the bottoms of the portions 34 and 35 is not in a straight line, but dips down toward the bend 36 to form a lower point 42 which is at a level at or slightly below the under faces of the feet 37 and 38 as best indicated in Figs. 2 and 4.

The bracket 18 is placed on the top side of the bar 11, Fig. 8, and has its inner end portions of the feet 37 and 38 resting on the top side of the bar 11 with the point 42 also in contact therewith. The bolt 16 is straddled by the inner edges 39 and 40 of the feet 37 and 38 so that the bracket 18 may be advanced or retracted along the bar 11 in reference to the cross bar 10. The feet 37 and 38 are engaged under bar 10 and over the bar 11.

Thus the brackets 17 and 18 may be suitably adjusted longitudinally of the bar 11 to secure the required spacing apart therebetween so as to receive the lower end of the tree trunk, for example, designated by the numeral 45 therebetween to be gripped by those brackets at the outward bends of the V portions 21 of the brackets 17 and 36 of the bracket 18.

Due to the weight or load of the tree trunk 45, the tendency will be for the bars 10 and 11 to bend downwardly between their outer end feet 12, these bars 10 and 11 being purposely made to be flexible and to bend slightly accordingly according to the load, without the end of the bolt 16 coming into contact with the supporting floor. The brackets 17 and 18 are initially pushed up against the opposite sides of the member 45 to bring them into snug, holding conditions. The weight of the member 45 bending the bars 10 and 11 cause the upper ends of the brackets 17 and 18 to lean inwardly by reason of that bending action, since the points 29 and 42 are spaced outwardly from the central portions of the bars. This causes the upper end portions of the brackets 17 and 18 to bear more snugly against an upper portion of the member 45 to increase the gripping action accordingly.

The two brackets 17 and 18 may be interengaged in a clamping action by means of bolts 47 and 48 passing through the perspective portions 19 and 20 of the bracket 17, and 32 and 33 of the bracket 18, such as by extending through the holes 49, 50 and 51, 52 therein respectively. The use of these clamp bolts 47 and 48 does not interfere with the additional clamping effect of the upper end portions of the brackets 17 and 18 due to the tendency of the members 10 and 11 to bow downwardly under load.

Furthermore, by reason of the flexibility of these members 10 and 11, the feet 12 will adjust themselves to be in firm contact with the floor, and furthermore by reason of the outwardly inclined sections 13 at each of the feet 12, there will be a tendency for the contacting portions 14 to grip in effect the floor so as to resist skidding along over the floor should the base be accidentally struck.

The bolt 16 carries a wing nut preferably, designated by the numeral 53 so that the bars 10 and 11 may be securely clamped in the crossed positions to engage the feet 37 and 38 therebetween after the initial adjustment is had of the bracket 18 in reference to spacing from the bracket 17. Also the nut 53 may be released when the base is to be demounted and stored.

Therefore, while I have shown herein my invention in the one particular form as described in minute detail, it is obvious that structural variations may be employed without departing from the spirit of the invention, and I therefore do not desire to be limited to that precise form beyond the limitations which may be imposed by the following claims.

I claim:

1. A base stand for supporting a pole-like

member in substantially vertical alignment comprising a pair of resilient bars; a foot downturned of each of the outer end portions of each bar; said bars having an approximately centrally located hole therein; a bolt to pass through said holes to maintain the bars in criss-crossed relation; a bracket having a lower opening to receive one of said bars therethrough; a bearing point on said bracket spaced outwardly from vertical alignment with said bracket opening, said point being located to bear on said one bar upon positioning said bracket in approximately a vertically disposed position whereby the margin of the lower side of said bracket opening bears against the underside of said one bar and said point bears on the top side of the bar at a distance removed from said margin bearing outwardly from said bar hole; and a second bracket; foot means extending substantially at right angles to the second bracket from its lower portion; said foot means having a slot to receive said bolt therein; and a bearing point carried by said second bracket positioned at the lower end of the bracket to be not higher on the bracket than the plane of the underside of said foot means; whereby said two brackets may be positioned along said one bar to be spaced apart to clamp said pole-like member therebetween.

2. A base stand for supporting a pole-like member in substantially vertical alignment comprising a pair of resilient bars; a foot downturned on each of the outer end portions of each bar; said bars having an approximately centrally located hole therein; a bolt to pass through said holes to maintain the bars in criss-crossed relation; a bracket having a lower opening to receive one of said bars therethrough; a bearing point on said bracket spaced outwardly from vertical alignment with said bracket opening, said point being located to bear on said one bar upon positioning said bracket in approximately a vertically disposed position whereby the margin of the lower side of said bracket opening bears against the underside of said one bar and said point bears on the top side of the bar at a distance removed from said margin bearing outwardly from said bar hole; and a second bracket; foot means extending substantially at right angles to the second bracket from its lower portion; said foot means having a slot to receive said bolt therein; and a bearing point carried by said second bracket positioned at the lower end of the bracket to be not higher on the bracket than the plane of the underside of said foot means; whereby said two brackets may be positioned along said one bar to be spaced apart to clamp said pole-like member therebetween; said foot means being clamped between said bars at their crossing by said bolt.

3. A base stand for supporting a pole-like member in substantially vertical alignment comprising a pair of resilient bars; a foot downturned on each of the outer end portions of each bar; said bars having an approximately centrally located hole therein; a bolt to pass through said holes to maintain the bars in criss-crossed relation; a bracket having a lower opening to receive one of said bars therethrough; a bearing point on said bracket spaced outwardly from vertical alignment with said bracket opening, said point being located to bear on said one bar upon positioning said bracket in approximately a vertically disposed position whereby the margin of the lower side of said bracket openings bears

against the underside of said one bar and said point bears on the top side of the bar at a distance removed from said margin bearing outwardly from said bar hole; and a second bracket; foot means extending substantially at right angles to the second bracket from its lower portion; said foot means having a slot to receive said bolt therein; and a bearing point carried by said second bracket positioned at the lower end of the bracket to be not higher on the bracket than the plane of the underside of said foot means; whereby said two brackets may be positioned along said one bar to be spaced apart to clamp said pole-like member therebetween; each of said brackets consisting of a generally flat plate with a centrally and vertically disposed outwardly extending V depression; and said bearing point in each instance being at the apex of the depression.

4. A base stand for supporting a pole-like member in substantially vertical alignment comprising a pair of resilient bars; a foot downturned on each of the outer end portions of each bar; said bars having an approximately centrally located hole therein; a bolt to pass through said holes to maintain the bars in criss-crossed relation; a bracket having a lower opening to receive one of said bars therethrough; a bearing point on said bracket spaced outwardly from vertical alignment with said bracket opening, said point being located to bear on said one bar upon positioning said bracket in approximately a vertically disposed position whereby the margin of the lower side of said bracket opening bears against the underside of said one bar and said point bears on the top side of the bar a distance removed from said margin bearing outwardly from said bar hole; and a second bracket; foot means extending substantially at right angles to the second bracket from its lower portion; said foot means having a slot to receive said bolt therein; and a bearing point carried by said second bracket positioned at the lower end of the bracket to be not higher on the bracket than the plane of the underside of said foot means; whereby said two brackets may be positioned along said one bar to be spaced apart to clamp said pole-like member therebetween; said first bracket being generally a flat plate having a centrally and vertically disposed V extension from its outer face, the lower end of the extension terminating above the lower edge of the plate, and a pair of legs extending one toward the other and substantially within the plane of the plate, the upper edges of said legs being spaced below said extension end to constitute said opening margin.

5. A base stand for supporting a pole-like member in substantially vertical alignment comprising a pair of resilient bars; a foot downturned on each of the outer end portions of each bar; said bars having an approximately centrally located hole therein; a bolt to pass through said holes to maintain the bars in criss-crossed relation; a bracket having a lower opening to receive one of said bars therethrough; a bearing point on said bracket spaced outwardly from vertical alignment with said bracket opening, said point being located to bear on said one bar upon positioning said bracket in approximately a vertically disposed position whereby the margin of the lower side of said bracket opening bears against the underside of said one bar and said point bears on the top side of the bar at a distance removed from said margin bearing outwardly from said bar hole; and a second bracket; foot means extending substantially at right an-

gles to the second bracket from its lower portion; said foot means having a slot to receive said bolt therein; and a bearing point carried by said second bracket positioned at the lower end of the bracket to be not higher on the bracket than the plane of the underside of said foot means; whereby said two brackets may be positioned along said one bar to be spaced apart to clamp said pole-like member therebetween; said first bracket being generally a flat plate having a centrally and vertically disposed V extension from its outer face, the lower end of the extension terminating above the lower edge of the plate, and a pair of legs extending one toward the other and substantially within the plane of the plate, the upper edges of said legs being spaced below said extension end to constitute said opening margin; said first bracket bearing point being located at the central point of said extension lower end.

6. A base stand for supporting a pole-like member in substantially vertical alignment comprising a pair of resilient bars; a foot downturned on each of the outer end portions of each bar; said bars having an approximately centrally located hole therein; a bolt to pass through said holes to maintain the bars in criss-crossed relation; a bracket having a lower opening to receive one of said bars therethrough; a bearing point on said bracket spaced outwardly from vertical alignment with said bracket opening, said point being located to bear on said one bar upon positioning said bracket in approximately a vertically disposed position whereby the margin of the lower side of said bracket opening bears against the underside of said one bar and said point bears on the top side of the bar at a distance removed from said margin bearing outwardly from said bar hole; and a second bracket; foot means extending substantially at right angles to the second bracket from its lower portion; said foot means having a slot to receive said bolt therein; and a bearing point carried by said second bracket positioned at the lower end of the bracket to be not higher on the bracket than the plane of the underside of said foot means; whereby said two brackets may be positioned along said one bar to be spaced apart to clamp said pole-like member therebetween; said bars being characterized by an elastic downwardly bending action between their feet under weight of said pole-like member to cause said brackets to tend to rock by their upper ends one toward the other.

7. A base stand for supporting a pole-like member in substantially vertical alignment comprising a pair of resilient bars; a foot downturned on each of the outer end portions of each bar; said bars having an approximately centrally located hole therein; a bolt to pass through said holes to maintain the bars in criss-crossed relation; a bracket having a lower opening to receive one of said bars therethrough; a bearing point on said bracket spaced outwardly from vertical alignment with said bracket opening, said point being located to bear on said one bar upon positioning said bracket in approximately a vertically disposed position whereby the margin of the lower side of said bracket opening bears against the underside of said one bar and said point bears on the top side of the bar at a distance removed from said margin bearing outwardly from said bar hole; and a second bracket; foot means extending substantially at

right angles to the second bracket from its lower portion; said foot means having a slot to receive said bolt therein; and a bearing point carried by said second bracket positioned at the lower end of the bracket to be not higher on the bracket than the plane of the underside of said foot means; whereby said two brackets may be positioned along said one bar to be spaced apart to clamp said pole-like member therebetween; said bars being elastic to sink centrally under load of said pole-like member; said feet being down and outturned end portions of the bars; said central sinking of the bars causing said feet

each to bear on a floor support and to rock outwardly the feet to tend to spread them apart.
